UNITED STATES PATENT OFFICE.

ZACHRY T. FURBISH, OF PHILADELPHIA, PENNSYLVANIA, ASSIGNOR TO THE NORTH BROTHERS MANUFACTURING COMPANY, OF SAME PLACE.

TOOL-HANDLE FASTENING.

SPECIFICATION forming part of Letters Patent No. 659,523, dated October 9, 1900.

Application filed April 12, 1900. Serial No. 12,602. (No model.)

To all whom it may concern:

Be it known that I, ZACHRY T. FURBISH, a citizen of the United States, residing at Philadelphia, Pennsylvania, have invented certain 5 Improvements in Means for Securing Handles to Tools, of which the following is a specification.

The object of my invention is to provide a simple and effective means for securing handles to tools.

My invention is especially adapted for securing the handles of ratchet screw-drivers and drills to the body of the device.

In the accompanying drawings, Figure 1 is 15 a side view of a ratchet screw-driver, illustrating my invention, the sleeve at the handle being in section. Fig. 2 is a longitudinal sectional view of Fig. 1, and Fig. 3 is a detached perspective view showing the means 20 for attaching the handle to the body of the tool.

A is the body of the tool, which in the present instance is in the form of a tube attached to the ratchet-carrier B. Within the 25 tube is the threaded stem C, carrying at its end a chuck C'.

D is a handle. In the present instance this handle is of wood and has a reduced portion D'. The handle is bored out to fit the tubular body A of the tool, and the portion D' of 30 the handle is slotted at d, so as to allow the sections formed between the slots to yield when the body portion is driven in place.

The body portion A is grooved at a, and in 35 the groove is placed a ring E, and in the reduced portion D' of the handle is an internal annular groove d'. The ring E is of such a diameter that it will partly enter the groove a in the body A and also enter the internal 40 groove d' in the handle. The ring is split, as shown, and is preferably made of spring metal.

In placing the ring in position I expand it, so 45 that it will pass over the body portion A and spring into the groove a. Then when the handle is forced onto the body portion the sections of the reduced portion D' will yield to allow the ring to pass and enter the internal groove d', thus locking the handle and the 50 body portion together.

A sleeve F is placed over the body portion, as well as over the reduced portion of the handle, and is preferably secured to the two elements by a screw f, Fig. 2. This flange prevents the sections of the reduced portion D' of the handle from yielding, and consequently firmly locks the body portion to the handle.

In order to prevent the body portion from turning in the handle, I secure in the end of the opening in the handle a tube G, notched 60 at g, so as to engage the notched end portion a' of the body A. This tube G also acts to relieve the ring E of end strain, as the thrust is taken directly by this tube.

While I have shown an almost complete 65 ring, it will be understood that a segment of a ring may be used and that while I have shown the body portion tubular it may be solid and the stop G in the handle may also be solid without departing from my invention, and in some instances the ring may be 70 fixed to the body portion or formed thereon.

I claim as my invention—

1. The combination of a handle having a split portion, an internal annular groove in 75 the split portion, a body portion, a projection on the body portion resting in the groove in the handle, and means for holding the split portion of the handle, substantially as described.

2. The combination of a handle having a split portion and an internal annular groove in the split portion of the handle, the body portion of a tool, a groove therein, a ring or segment resting in the groove in the body portion and the groove in the handle, and means for holding the split portion of the handle, substantially as described.

3. The combination of a handle having a split portion and having an internal annular 90 groove in the split portion, a body portion having an annular groove therein, a ring resting in the two grooves, and a sleeve on the split portion of the handle, substantially as described.

4. The combination of a handle having an opening therein, a notched piece within the opening, a body portion notched at the end to engage the notched piece of the handle, an annular groove in the body portion, an inter- 100

nal annular groove in the handle, and a ring or a segment of a ring resting in the grooves, substantially as described.

5. The combination of a handle, an opening therein, a body portion within the opening, the end of the handle being split and having an internal annular groove, an annular groove in the body portion, a ring or a segment of a ring resting in the grooves, and a
10 sleeve fitting snugly over the end of the han-

dle and on the body portion, thus preventing the split portion of the handle from yielding, substantially as described.

In testimony whereof I have signed my name to this specification in the presence of 15 two subscribing witnesses.

ZACHRY T. FURBISH.
